UNITED STATES PATENT OFFICE.

THOMAS OSBORN, OF CENTERVILLE, IOWA.

SPARK PLUG.

Application filed August 14, 1923. Serial No. 657,400.

One object of this invention is to provide a spark plug which is so constructed that leakage of compression and the passing of oil through the plug will be reduced to a minimum, a substantially hermetic closure being effected without appreciable danger of breaking the core of the plug.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in longitudinal section, a plug constructed in accordance with the invention, parts being in elevation; Figure 2 is a cross section on the line 2—2 of Figure 1; Figure 3 is a cross section on the line 3—3 of Figure 1; Figure 4 is a cross section on the line 4—4 of Figure 1.

The plug forming the subject matter of this application comprises a metal casing 1 which is externally threaded as at 2 for engagement with the cylinder of an internal combustion engine. At its inner end, the casing 1 has a bore 3, the inner end of the casing carrying an electrode 4. The casing 1 has an internal shoulder 5 which is inclined toward the inner end of the plug, the shoulder being located at one end of the bore 3. The casing 1 has an internal shoulder 6 located at right angles to the axis of the casing 1. The casing 1 is provided with an external wrench-receiving part 7.

The core of the plug is marked by the numeral 8 and is made of porcelain or any other suitable substance. The core 8 includes a neck 9, an enlarged body 10 and a reduced foot 11 provided with a recess 12 defining an internal shoulder 14 located in the body 10 of the core. The body 10 of the core has an inclined surface 15 disposed parallel to the inclined shoulder 5 in the casing 1. At a point adjacent to the shoulder 6 in the casing 1, the body 10 of the core 8 has an inclined surface 16 which slopes in a direction opposite to that

in which the surface 15 slopes. A compressible washer 17, made of copper and asbestos or any other suitable materials, rests on the shoulder 5 of the casing 1 and receives the foot 11 of the core, the washer 17 being bound between the shoulder 5 and the inclined surface 15 of the body 10 of the core 8. A compressible washer 18 rests on the shoulder 6 of the casing 1 and is beveled as at 19, to cooperate with the inclined surface 16 of the body 10 of the core 8. A metal washer 21 is located in the casing 1 and rests on the washer 18. Both the upper and lower surface of the metal washer 21 preferably are smooth. A sleeve 22 is threaded into the casing 1 and has a rounded lower end 23 bearing on the washer 21.

An electrode 24 extends through the core 8 longitudinally thereof, the same being provided intermediate its ends, with a projection 25 engaging an asbestos washer 50 bearing against the shoulder 14 which exists at the inner end of the recess 12 in the core 8. A washer 26 surrounds the electrode 24 and engages the upper end of the core 8, a binding nut 27 being threaded on the end of the electrode 24 and the washer 26 being interposed between the nut 27 and the core 8.

In practical operation, when the sleeve 22 is threaded into the body 1, the sleeve rotates readily on the metal washer 21, because the lower end of the sleeve is rounded as at 23. Owing to the fact that the washer 21 is interposed between the sleeve 22 and the washer 18, the last mentioned washer is not worn unduly, or injured by contact with the sleeve 22. The washer 18 is compressed and expands inwardly bridging the space between the casing 1 and the core 8, the washer 18 cooperating with the inclined surface 16 of the body 10 of the core 8 to secure an hermetic closure. When the core 8 is crowded downwardly into the casing 1 by the action of the sleeve 22, the compressible washer 17, cooperating with the inclined surface 5 of the casing 1 and with the surface 15 of the body 10 of the core 8, is compressed and is caused to expand inwardly, the washer enclosing the foot 11 of the core and providing an hermetic closure. It will be seen from the foregoing that the plug is sealed at two places, longitudinally of the plug and that a leakage of compression will be practically impossible, the compressible washers 17 and 18 preventing the core 8 of the plug from being broken when the sleeve 22 is advanced.

The core of the plug is marked by the numeral 8 and is made of porcelain or any other suitable substance. The core 8 includes a neck 9, an enlarged body 10 and a reduced foot 11 provided with a recess 12 defining an internal shoulder 14 located in the body 10 of the core. The body 10 of the core has an inclined surface 15 disposed parallel to the inclined shoulder 5 in the casing 1. At a point adjacent to the shoulder 6 in the casing 1, the body 10 of the core 8 has an inclined surface 16 which slopes in a direction opposite to that

What is claimed is:

A spark plug comprising a casing; a core in the casing; a compressible gasket within the casing and about the core; a metal washer within the casing and about the core, the washer bearing upon the gasket and having a smooth outer surface; and a sleeve threaded into the casing and having a transversely rounded inner end surface which engages

the smooth outer surface of the washer, said surfaces cooperating to prevent the washer from rotating upon the gasket when the sleeve is rotated.

In testimony that I claim the foregoing as my own, I have hereto affixed my signature.

THOMAS OSBORN.
